UNITED STATES PATENT OFFICE

BERNARD KRASNOFF, OF BROOKLYN, NEW YORK

ARTIFICIAL DENTURE

Application filed February 20, 1928. Serial No. 255,801.

My invention relates to means for retaining artificial dentures, such as removable plates and bridge work, in place in the mouth, and the same has for its object more particularly to provide a simple, efficient and comfortable device which serves to supplement the plate or bridge straddling the gum or the anchorages thereof, or both, in retaining the same in place, and which readily permits of the removal and insertion of the denture.

Further, said invention has for its object to provide a device of the character specified which is attached to the plate and extends beyond the same in engagement with the gum for retaining the plate in place.

Further, said invention has for its object to provide a device of the character specified in which the gum engaging extension or tongue conforms to the contour of the surface of the gum to effect a comfortable extended surface engagement therewith.

Further, said invention has for its object to provide a device of the character specified in which the gum engaging extensions are adjustably attached to the plate to facilitate the insertion and removal of the device into and from the mouth.

Other objects will in part be obvious, and in part be pointed out hereinafter.

To the attainment of the aforesaid objects and ends, my invention consists in the novel features of construction, and in the combination, connection and arrangement of parts hereinafter more fully described and then pointed out in the claims.

In the accompanying drawing:

Fig. 1 is a perspective view showing one form of device constructed according to and embodying my said invention;

Fig. 2 is a side view thereof;

Fig. 3 is a detail view partly in section;

Fig. 4 is a rear view of the gum engaging extension or tongue;

Fig. 5 is a transverse sectional view thereof; on the line 5—5 of Fig. 2;

Fig. 6 is a side view showing a modification; and

Fig. 7 is a sectional view thereof.

Referring to the drawing, I have illustrated the denture as applied to the upper

gum A. The denture consists of the usual plate 12 straddling the gum and having the artificial teeth 14 set therein.

The means for retaining the denture in place comprises a pair of extensions or tongues 18 which extend upwardly from the plate 12 and inwardly towards each other. The tongues or extensions 18 conform in contour with the contour of the surface of the gum with which they engage, and the same are curved to extend over the bulging portion of the gum, as indicated at B, into the hollow or recessed portion thereof, as indicated at C. The contour of the tongues 18 is obtained from the impressions taken of the jaw in the same manner that the contour of the plate 12 is obtained.

As illustrated at Figs. 1 to 5, the plate 12 is provided with relatively thickened portions 20 having sockets 22 therein to receive the prongs 24 of the members 18. The gum engaging portions 20 are separate at the front to expose the natural gum, the lengthwise movable members 18 extending inwardly towards each other from the separated portions 20 and engaging the gum therebetween. The prongs 24 are preferably slotted at the ends 26 thereof to provide a resilient frictional engagement with their sockets 22 to permit of the sliding adjustment thereof.

At Figs. 6 and 7 the relatively thickened portions 20 are provided with slots or recesses 28 in which the L-shaped prongs 30 of the members 18a are received, providing a close fit and a frictional sliding engagement. The angular ends of the prongs 30 limit the outward travel of the members 18a. A plate 32 secured by screws 34 serves to retain the members 18a in place with the prongs 30 thereof within the slots or sockets 28.

When the members 18, 18a are partially pulled out of their sockets, the device can be readily placed in the mouth and secured in position by pushing the members 18, 18a into their sockets to cause said members to firmly engage the gum. The device is readily removed by partially pulling out the said members 18, 18a to release their engagement with the gum.

When the denture is in place in the mouth,

the tongues 18, 18a, engaging over the ridge B of the gum and extending into the depression C thereof, securely retain the denture in place, exerting a gentle and evenly distributed pressure over the surface of the gum, and providing an efficient holding device which may be worn with comfort. The members 18, 18a may be readily removed and replaced as required. The subject matter of my invention disclosed herein and not claimed is disclosed and claimed in my co-pending application Serial No. 255,800, filed February 20, 1928.

I claim:

1. A device of the character described comprising a plate having teeth thereon, and a separate tongue projecting from said plate and adapted to engage an exposed portion of the natural gum for securing the device in place, said tongue being slidable relative to said plate to secure and release the device.

2. A device of the character described comprising a plate having a gum engaging portion, and a tongue member thereon extending circumferentially of the gum and substantially conforming in contour therewith, said tongue member being connected to said gum engaging portion for lengthwise movement to secure the device in place and to release the same.

3. A device of the character described comprising a plate having a gum engaging portion provided with a socket, and a gum engaging member extending circumferentially of the gum and slidably received at its inner end within said socket, said gum engaging member being adjustable within the socket thereof for securing and releasing the device.

4. A device of the character described comprising a plate having artificial teeth thereon, a pair of members projecting upwardly from said plate and engaging the gum beyond the same; said members being slidably attached to said plate.

5. A device of the character described comprising a plate having artificial teeth thereon, and a socket portion, and a gum engaging member having a pronged portion secured within said socket portion, and slidable therein.

6. A device of the character described comprising a plate having artificial teeth thereon, and relatively thickened portions adjacent to the ends thereof provided with sockets, and members having prongs slidably secured within said sockets, and extending inwardly towards each other above said plate; said members conforming in contour with the contour of the gum engaged thereby.

7. A device of the character described comprising a plate having artificial teeth thereon, and a relatively thickened portion provided with recesses, a gum engaging member provided with L-shaped prongs adjustably

secured within said recesses, and a member secured over said recesses for retaining said gum engaging member in place.

8. A device of the character described comprising a plate having gum engaging portions separated at the front to expose a portion of the natural gum, and tongue members projecting from said gum engaging portions and extending inwardly towards each other circumferentially of the exposed gum portion, said tongue members being connected to said gum engaging portions for lengthwise movement into and out of engagement with said gum portion to secure the device in place and to release the same.

In testimony whereof, I have signed my name hereto.

BERNARD KRASNOFF.
